CLAIM

The ornamental design for a display screen with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen with a graphical user interface.

The broken lines showing a display screen illustrate portions of the article, and form no part of the claimed design.
